Attorney

UNITED STATES PATENT OFFICE.

WARD A. EITELBUSS, OF ST. JOHNS, MICHIGAN.

MITER-BOX ATTACHMENT.

1,333,103.

Specification of Letters Patent.

Patented Mar. 9, 1920.

Application filed December 14, 1918. Serial No. 266,768.

To all whom it may concern:

Be it known that I, WARD A. EITELBUSS, a citizen of the United States, residing at St. Johns, in the county of Clinton and State of Michigan, have invented certain new and useful Improvements in Miter-Box Attachments, of which the following is a specification.

This invention has reference generally to improvements in attachments for miter boxes and more particularly relates to a board rest.

The invention has for its principal aim and object to provide a device of the above mentioned character designed to be used in conjunction with a miter box to serve as a rest for long pieces of material, molding, casings, et cetera, at the time the latter are being cut and is capable of being attached directly to the end of a miter box or to the work-bench in spaced relation to the miter box.

More particularly this invention embraces the provision of a device of the above mentioned character wherein the base of the attachment is formed with a guard and has mounted above the base a feeding roller which facilitates the movement of the board which is being cut while the base is supported so that the roller will have its upper surface positioned and substantially flush with the upper face of the miter box so as not to interfere with an effective use of the miter box.

It is a more specific object of this invention to provide a device of the above mentioned character wherein the component parts are of novel construction and are relatively adjustable so that when not in use the device may be placed in a small compact form so as to only occupy a minimum amount of space in a tool box or the like.

Among the other aims and objects of this invention may be recited the provision of a device of the above mentioned character wherein the number of parts are comparatively few, the construction simple, the cost of production low and the efficiency high.

Other objects as well as the nature, characteristic features and scope of this invention will be more readily apparent from the following description taken in connection with the accompanying drawings, and pointed out in the claims, forming a part of this specification.

The invention is clearly illustrated in the accompanying drawings, in which:—

Figure 1 is a perspective view showing the device attached to the end of a miter box only a portion of which latter is shown, 60

Fig. 2 is a perspective view showing the arrangement of the parts when the device is attached to a work bench or the like and in spaced relation to a miter box.

Fig. 3 is a transverse sectional view 65 through the device, and

Fig. 4 is a longitudinal sectional detail showing the roller mounting.

Similar characters of reference are employed in all of the above described views, to 70 indicate corresponding parts.

Referring now, more particularly, to the accompanying drawings there is provided a base 1 which may be and preferably is formed of metal while the upper surface is 75 provided with a longitudinally extending and transversely curved bottomed groove 2 for a purpose that will presently appear. A relatively short bearing standard 3 is formed integral with one end of the base 80 while an upright guard arm 4 is formed integral with the opposite end of the base and is provided with a bearing opening 5 opposite to the opening in the bearing standard 3. A roller 6 is journaled in the bearing 85 and the guard arm and has its lowermost portion disposed within and arranged in closely spaced relation with the bottom of the groove 2. One trunnion 7 of the roller is stationary being desirably journaled in the bearing standard 3 while the opposite trunnion 8 is in the form of a set-screw, the outermost portion of the shank of which is threaded as at 9 and detachably engaged in a correspondingly threaded recess 10 in the 90 adjacent end of the roller, the inner portion of the shank being journaled in the opening 5 while the knurled head 11 on the outer ends of the shank facilitates the application of the trunnion and by this arrangement it 95 is apparent that the roller can be removed when desired.

The base is also provided with transversely extending openings 12, through which are passed fastening devices 13 designed for engagement with the adjacent end edge of a miter box 14, only a portion of which is shown, for the supporting of the base and the maintenance of the upper surface of the roller substantially flush with 110

the upper surface of the miter box to facilitate the adjustment of a board or other piece of material (not shown), as is apparent. As intimated, the device has been designed so that it is capable of being supported independently of the miter box in spaced relation thereto. In reducing this feature of the invention to practice, there is employed a stand which consists of coacting arched supporting members 15 and 16, the medial portion 17 of the member 15 is connected to the under surface as by suitable fastening screws 18 while the side portions of this member serve as legs 19 and terminate in outwardly projecting attaching feet 20. The medial portion 21 of the member 16 is swiveled at a point intermediate its ends to the under surface of the medial portion 17 as by a bolt 21, the head 22 of which is countersunk in the upper face of the member or portion 17 preparatory to the attaching of this portion to the base. The side portions of the member 16 constitute attaching and supporting legs 23 and are designed to lie in close relation with the inner surfaces of the legs 19 when the medial portions aline with each other and when the device is not in use so that it will only occupy a minimum amount of space and may be easily accommodated in a tool kit or box as is apparent. On the other hand, when the member 16 is arranged at right angles to the member 15 the legs 23 will coact with the legs 19 in properly supporting the base. A suitable clamping element such as a wing nut 24 is employed and is engaged with the depending threaded portion of the bolt 21 for clamping the members 15 and 16 in their relative positions of adjustment, as is apparent.

It is believed in view of the foregoing description that a further detailed description

of the operation of the invention is entirely unnecessary. Likewise, it is believed that the advantages of the invention will be readily apparent.

Still further embodiments of the invention than those herein especially defined may be resorted to as conditions or preference may dictate, as may be in keeping with the hereto appended claims.

Having thus fully described the invention what is claimed as new and desired to be secured by Letters Patent, is:

1. A device of the character described, comprising a pair of inverted substantially U-shaped supports, one fitted within the other, a clamp pivotally connecting the interfitted supports medially of the same, whereby the supports can be moved in cross relation to each other and in alinement with one another, a base fixed to one of the supports and having a short bearing standard and a relatively long bearing standard rising therefrom, and a roller journaled in said standards parallel with the base.

2. A device of the character described, comprising a pair of inverted substantially U-shaped supports, one fitted within the other, a clamp pivotally connecting the interfitted supports medially of the same, whereby the supports can be moved in cross relation to each other or into alinement with one another, a base fixed to one of the supports and having a short bearing standard and a relatively long bearing standard rising therefrom, a roller journaled in said standards parallel with the base, and fasteners carried in the base for permitting the attachment thereof to a miter box.

In testimony whereof I affix my signature hereto.

WARD A. EITELBUSS.
